Affidavit

UNITED STATES PATENT OFFICE.

GEORGE H. FORSYTH, OF CHICAGO, ILLINOIS, ASSIGNOR TO WAUGH DRAFT GEAR COMPANY, A CORPORATION OF ILLINOIS.

DRAFT-RIGGING FOR RAILWAY-CARS.

1,123,510.

Specification of Letters Patent.

Patented Jan. 5, 1915.

Application filed October 18, 1905. Serial No. 283,273.

To all whom it may concern:

Be it known that I, GEORGE H. FORSYTH, a citizen of the United States, residing at Chicago, in the county of Cook and State 5 of Illinois, have invented certain new and useful Improvements in Draft-Rigging for Railway-Cars, of which the following is a specification.

This invention has to do with draft-rigging mechanism, and among other objects it is intended to provide simple and efficient means for yieldably confining the yoke or draw-bar extension. With the present tendency to allow the draw-bars of cars increased freedom of side movement when rounding curves, it has become necessary to provide some means for maintaining the normal or central position of the draw-bar and its extension.

Generally speaking, there are three forms 20 of construction permitting lateral movement to the draw-bar. In the first, the yoke or draw-bar extension is rigidly connected to the end of the draw-bar and both are allowed to have angular movement relative to the rest of the draft-rigging mechanism. In the second, the draw-bar is pivotally connected to the yoke, in which case a limited amount of side movement is given the latter. 25 Lastly, the draw-bar, yoke and draft-rigging mechanism as a whole have a pivotal connection with the car.

My invention is intended not merely or primarily to produce a means for returning 30 the draw-bar and maintaining the same in a central or coupling position, but it has as a further object, particularly in the first of the above-described forms of construction to afford a means for normally maintaining or returning the draw-bar extension or yoke 35 upon or to the longitudinal center line of the car. I accomplish this latter object by providing a guide, which, while permitting angular movement of the yoke, normally 40 maintains the latter under yielding engagement therewith substantially upon the center line of the car.

Heretofore it has been customary to construct the draft-rigging mechanism with 45 transversely disposed followers whose ends have abutted stop members rigidly attached to the draft-sills of the car; and between said stop members there has been provided a yoke encircling the followers and resist- 50 a yoke encircling the followers and resist- ance medium of the draft-rigging. In or-

der to maintain the yoke substantially central between the draft-sills rigid guides have been employed which, in some cases consist of the follower stops themselves or inwardly projecting central portions of the 60 draft castings with which the follower stops have been integral. The result has been that after a very limited angular side movement of the draw-bar the yoke has been drawn into engagement with these rigid guides, 65 whereby further strains upon the draw-bar tending to move the latter to one side have produced excessive breaking or shearing strains upon the rivets or the connections uniting the draw-bar and yoke. 70

In my present invention the extension or yoke guides are adapted to have movement under engagement with the extension or yoke whereby during angular movement of the draw-bar the injurious side strains are 75 practically done away with, while at the same time the extension or yoke is normally maintained in its proper position by the spring-actuated guide, when the draw-bar is free. 80

Another object of my invention is to provide a device for centering or effecting the side movement of the draw-bar or yoke under an engagement therewith that will permit either the draw-bar or yoke, or both, to 85 be jerked free of the car without injury to said device. It has been common heretofore in the case of draw-bars for freight cars, to increase the height of the draw-bar at its inner end to form a boss or abutment about 90 which the adjacent ends of the yoke are lipped, in order to add to the strength of the connection. There have been devised draw-bar actuating devices, one or more of whose parts have extended transversely of 95 the draw-bar. These devices, however, have been so constructed that the said part or parts have been liable to be struck by the enlarged end of the draw-bar, in case the latter has been torn from the car, with the 100 result of injuring the actuating device. In my present invention I provide a device which, while operating transversely of the draw-bar, will permit the latter, or the yoke, or both, to be torn free from the car with- 105 out injury thereto.

In association with my present improvements I may also employ a centering device for the draw-bar stem or shank, although such a centering device is not necessary, ex- 110

cept in constructions wherein the draw-bar stem is pivotally connected to the forward end of the draw-bar extension or yoke. In construction wherein the draw-bar is rigid with the yoke, a truck-actuated form of centering device tending to normally maintain the draw-bar substantially in the line of draft or at right angles to the truck may be useful.

10 Approved forms of my invention are illustrated in the accompanying drawings, in which,

Figure 1 is a top plan view of a draft-rigging embodying one form of the invention; Fig. 2 is a similar view of a modified form of the invention, showing also a draw-bar centering means; Fig. 3 is a cross-sectional view on the line 3—3 of Fig. 1; Fig. 4 is a cross-sectional view on the line 4—4 of Fig. 2; Fig. 5 is a cross-sectional view on the line 5—5 of Fig. 2; Fig. 6 is a side elevational view, broken away, of the draw-bar and yoke extension; Fig. 7 is a detail cross-sectional view similar to Fig. 3, and illustrating a modified form of the latter; Fig. 8 is a top plan view of a form wherein the entire draft-rigging is pivoted relatively to the car-body; and Figs. 9 and 10 are cross-sectional views on the lines 9—9 and 10—10, respectively, of Fig. 8.

Referring to the drawings, 10 may designate the draft sills, which may be either the channel center sills of a steel car, or may be separate sills secured to the usual center sills. Secured to the inner faces of said sills are the usual front and rear stop castings 11 and 12, respectively, between which is mounted the draw-bar extension or yoke 13, with considerable side clearance between itself and both the front and rear stops. Disposed between and transversely of the upper and lower sections of the yoke are front and rear followers 14 and 15, respectively, the ends of which engage the follower stops in the usual manner. Within the yoke and abutting against the inner faces of the followers is the usual draft and buffing spring 16.

17 designates the draw-bar rigidly connected as by rivets 18 to the forward end of the yoke 13 (Fig. 6), and terminating at its outer end in the usual coupler head partially indicated at 19.

The parts as thus far described are usual and common in present draft-rigging practice, excepting for the fact that the parts are so assembled as to permit a considerably wider lateral movement of the yoke than in present practice.

60 Referring now to an important feature of my present invention whereby the yoke is equipped with elastic yielding guides which, while normally maintaining its central position, permit it to partake of the lateral deflection of the draw-bar without any sub-

stantial strain on the connections between the latter and the yoke, 20 designates a pair of yoke guides disposed on opposite sides of the upper section of the yoke, respectively; each of said guides in the form here-
in shown comprising a flat strip or bar equipped centrally thereof with an upstanding flange 21 constituting a spring abutment, the ends of said flange being preferably turned and continued across the face of the bar, as shown at 22; thereby forming a spring pocket as well as a reinforcement for the bar. The flanges 21 are apertured, and through said apertures, as also through corresponding apertures in the draft sills 10, is passed a bolt 23 (Fig. 3) secured in position by suitable heads or nuts 24. The bolt 23 lies above the upper section of the yoke; and on it, between the flanges 21 of the guides, is secured as by means of a cross-pin 25, a spacing sleeve 26 of a length substantially equal to the width of the yoke. Surrounding the bolt 23 on the outer sides of the guide flanges 21 are springs 27, said springs abutting at one end against the flanges of the guides and at their other end against the inner faces of the sills 10. It will be seen that the bolt 23 holds the yoke guides against vertical and longitudinal displacement; while the ends of said guides overlie the upper edges of the followers, as shown in Fig. 1, which, in coöperation with the bolt 23, prevents angular displacement of said guides.

It will be seen from the foregoing that in effect the draw bar and yoke are floatatively mounted within the space between the draft sills and are thus permitted bodily movement as distinguished from pivotal movement, subject only to the yielding control of the resistance springs acting longitudinally on the follower plates and laterally on the draft sills.

When the mechanism is idle or is working over straight track, the spring-pressed guides 20 lying upon the opposite sides of the yoke, maintain the same in central position substantially in alinement with the longitudinal median line of the car. When, however, the draw-bar is angularly deflected, the yieldable guides 20 permit the yoke to likewise partake of said angular movement of the draw-bar, without injurious shearing strains upon the rivets 18 connecting the yoke and draw-bar; the spring-pressed guides automatically tending to return the yoke, and consequently the draw-bar, to central position as soon as the coupler head is free, or the lateral strains are intermitted.

Fig. 7 illustrates a slight modification in the construction of the means for mounting the yoke guides; the same consisting in the substitution for the short sleeve 26 pinned to the bolt 23, of a sleeve extending

the full width of the draft-sills, said sleeve having reduced end portions 26^a that are surrounded by the springs 27, and an inner portion 26^b of greater diameter which provides annular shoulders to be engaged by the vertical flanges of the yoke guides. In Fig. 1 I have indicated at 17^a parts of a truck-actuating draw-bar controlling means, which may consist, for instance, of a pair 10 of chains connected to opposite sides of the draw-bar and to parts of the truck, whereby the draw-bar is maintained at right angles to the truck or substantially coincident with the line of draft, the yoke guides 15 yielding, when necessary, to permit such movement of the draw-bar.

The construction illustrated in Figs. 2, 4 and 5 embodies the same operative principle as that already described in a little different 20 mechanical form and as applied to a construction wherein the draw-bar is pivotally connected to the yoke as at 18^a. In this construction I provide the yoke with one or more inverted saddle-shaped members 30 25 that overlie and are adapted to embrace the upper section of the yoke, said members each having a central upstanding web 31 and transverse webs 32, thereby forming pockets for the inner ends of springs 33 on 30 either side thereof, said member and springs being mounted upon and guided by a transverse bolt 23^a secured in and between the draft-sills similar to the bolt 23. In Fig. 2 I have shown a pair of such devices located 35 on either side of the longitudinal center of the yoke. In the said figure I have also shown a similar device engaging the draw-bar or coupler shank 17 in advance of the pivotal connection of the yoke thereto. This 40 latter device is shown in cross-section in Fig. 5, wherein it will be seen that the construction is the same as that of Fig. 4, except that the depending sides of the saddle-shaped member 30^a are of greater length, in 45 order to reach the sides of the draw-bar while at the same time affording sufficient clearance for the passage of the yoke connections thereunder. In the construction shown in Fig. 2, the yoke-engaging guides 50 operate with each other in normally maintaining the yoke in central position while elastically permitting lateral or angular deflection thereof, so as to allow the yoke as well as the draw-bar to pull into the line of 55 draft.

Figs. 8, 9 and 10 illustrate an application of my invention to a construction wherein the entire draft-rigging is pivotally mounted relatively to the car, so as to partake of 60 such angular movement as is permitted by the spacing of the draft-sills.

34 and 35 designate a pair of supporting brackets secured to and between the draft-sills, between which brackets is pivotally 65 mounted a frame or casing 36 containing

the usual yoke, followers and draft and buffing spring, the corner walls of the casing serving as stops. The upper wall of the casing, in advance of the trunnion thereof, is provided with an upstanding protuberance 37 formed thereon (Fig. 10), the same being engaged by an inverted saddle-shaped member 30^a mounted and actuated in the manner and by the means shown in Fig. 4, whereby the draft-rigging casing or cage, 70 when angularly deflected and released, is returned, with its contained parts, to a position substantially coincident with the longitudinal median line of the car. Preferably the outer faces of the followers have rounded 75 surfaces engaging the draw-bar or its extension, as shown at 14^a in Fig. 1, whereby to permit free angular movement of the extension, these rounded surfaces preferably 80 assuming a convex form.

It will be observed that the yoke and draw-bar guides are located above the highest points of the yoke and above the highest points of such parts of the draw-bar as are in rear of said guides. In consequence of 90 this arrangement the yoke and draw-bar can, in case of accident, be pulled entirely clear of the end of the car without injury to the guides.

I am aware that it has heretofore been 95 proposed to employ spring-backed followers on the opposite sides of the yoke or draw-bar extension, and also to employ automatic centering devices in connection with centrally pivoted drawbar yokes or extensions. 100 My invention is radically distinguished from such constructions in that it employs, in coöperation with the drawbar yoke or extension, which is capable of bodily lateral movement, laterally yieldable confining 105 members that are entirely independent of the draft and buffing spring or springs, and have the function of automatically maintaining the yoke or drawbar extension axially coincident with the median line of the 110 car when free of laterally deflecting influences, whereby sufficient lateral movement of the yoke is afforded to avoid shearing strains upon the drawbar and yoke connections, and at the same time the drawbar is 115 automatically maintained, when free, in coupling position.

From the foregoing it will be evident that the principle of the above-described invention is capable of embodiment in other more or less differing forms all capable of effecting the same results and advantages; and hence I do not limit the invention to the particular form or forms herein shown and described, except to the extent indicated in 120 specific claims.

I claim:

1. In a draft rigging mechanism, the combination with the car, of a draw-bar, a draw-bar extension having lateral bodily move- 125

- ment independent of said car, a resistance medium, and means independent of the resistance medium adapted to yieldingly engage and center the said extension, substantially as described. 5
2. In a draft-rigging mechanism, the combination with the car, of a draw-bar and a draw bar extension bodily movable laterally independently of the car, a resistance medium, means independent of said resistance medium adapted to yieldingly engage the said extension at a plurality of points and normally tending to center the same, substantially as described. 10
3. In a draft-rigging mechanism, the combination with draft sills, of a draw-bar, a draw-bar extension and a resistance medium bodily movable laterally independently of said draft sills, spring-pressed guides independent of the resistance medium adapted to yieldingly engage the sides of said extension on both sides of the longitudinal center thereof, substantially as described. 15
4. In a draft-rigging mechanism, the combination with draft sills, of a draw bar, a draw-bar extension rigid therewith and having bodily lateral movement independently of said draft sills, a resistance medium, spring-pressed guides independent of the resistance medium adapted to yieldably confine said extension laterally on both sides of the longitudinal center thereof, substantially as described. 20
5. In a draft-rigging mechanism, the combination with draft sills, of a draw-bar, a draw-bar extension bodily movable laterally independently of said draft sills, a resistance medium disposed and operating parallel with said draw-bar extension, and spring-pressed guides adapted to yieldably confine said extension laterally on both sides of the longitudinal center thereof, substantially as described. 25
6. In a draft-rigging mechanism, the combination with draft sills, of a draw-bar and draw-bar extension bodily movable laterally independently of said sills, of a resistance medium and a yieldable guide for said draw-bar extension, the same comprising a pair of springs mounted to operate in a direction transversely of said extension, and thrust members actuated by said springs and engaging the opposite sides of said extension, substantially as described. 30
7. In a draft-rigging mechanism, the combination with a draw-bar and a draw-bar extension, of a yieldable guide for said draw-bar extension, the same comprising a pair of
- springs mounted to operate in a direction transversely of said extension, thrust members actuated by said springs and engaging the opposite sides of said extension, and a spacing sleeve between said thrust members, substantially as described. 60
8. In a draft-rigging mechanism, the combination with a draw-bar and a draw-bar extension, of a yieldable guide for said draw-bar extension, the same comprising a pair of springs operating in a direction transversely of said extension, a rod on which said springs are mounted, thrust members actuated by said springs and engaging the opposite sides of said extension, and a spacing sleeve secured to said rod between said thrust members, substantially as described. 65
9. In a draft-rigging mechanism, the combination with a draw-bar, and a draw-bar extension having bodily lateral movement, of a pair of yieldable guides operating laterally upon said draw-bar extension, and a follower having a rounded surface engaging said draw-bar extension whereby to permit free angular movement of said extension, substantially as described. 70
10. In a draft-rigging mechanism, the combination with a draw-bar, and a draw-bar extension having bodily lateral movement, of a pair of yieldable guides operating laterally upon said draw-bar extension, and followers having convexed outer surfaces whereby to permit free angular movement of said extension, substantially as described. 75
11. In a draft-rigging, the combination with a pair of draft sills, of a floating draw-bar and yoke loosely mounted within the space between the draft sills and spaced therefrom for bodily lateral movement, and yielding resistance media disposed laterally between the said yoke and the draft sills, substantially as described. 80
12. In a draft-rigging, the combination with a pair of draft sills having front and rear stops on the inner opposed faces thereof, of a floating draw-bar and yoke provided with front and rear follower plates and loosely mounted within the space between the draft sills and stops and spaced therefrom for bodily lateral movement, and yielding resistance media disposed laterally and longitudinally between the said yoke and the draft sills and the follower plates respectively, substantially as described. 85
